UNITED STATES PATENT OFFICE.

JOHN E. O'CONNOR, OF CHICAGO, ILLINOIS, ASSIGNOR, BY MESNE ASSIGNMENTS, TO
W. H. MINER, INC., A CORPORATION OF DELAWARE.

CONNECTER FOR MINE CARS AND THE LIKE.

Application filed September 28, 1923. Serial No. 665,310.

This invention relates to improvements in connectors for mine cars and the like.

One object of this invention is to provide a simple and relatively inexpensive connector, especially adapted for mine cars, wherein resilient means is provided for effectively cushioning the shocks in both buff and draft.

Other objects and advantages of the invention will more clearly appear from the description and claims hereinafter following.

In the drawing forming a part of this specification, Figure 1 is a vertical, longitudinal, sectional view of the adjacent ends of two mine cars, showing my improvements in connection therewith. Figure 2 is a top plan view of the structure illustrated in Figure 1. Figure 3 is a transverse, vertical, sectional view corresponding substantially to the line 3—3 of Figure 1. Figure 4 is a view similar to Figure 2, showing a different embodiment of the invention, and Figure 5 is a vertical sectional view corresponding substantially to the line 5—5 of Figure 4.

In said drawing, referring first to the construction illustrated in Figures 1, 2 and 3, each mine car is shown as provided with a suitable heavy flooring 10 and a vertical end wall 11. At the opposite ends, each car is also provided with a drawbar 12. Each drawbar is in the form of an elongated flat plate extending through the corresponding end wall 11 and secured at its inner end to the flooring 10. Adjacent the outer end, each drawbar 12 is provided with a downwardly projecting lug 13 abutting the end of the flooring 10. A bolt 14 extending through the drawbar, the outer end of the flooring 10 and a transversely extending reinforcing member 15 at the lower side of the flooring, is preferably provided to secure the outer end of the drawbar to the car.

The connecting or coupling means, proper, as shown in Figures 1, 2 and 3, preferably comprises a yoke member A; a pair of cups B—B; a set of spring plates C; and two blocks D and E swiveled to the respective drawbars of two adjacent cars.

The yoke member A comprises a shank 16 having a ring shaped eye 17 at one end and a head 18 at the opposite end. The head 18 comprises spaced side members 19—19 and a relatively heavy top connecting web 20. The side members 19 are connected to the

shank 16 by a pair of parallel arms 21 extending in the same direction and a transverse section 22 connecting the arms. The side members 19 of the head are provided with aligned journal openings as indicated at 23, and the upper surface of the web 20 forming the top of the head 18 is rounded off as indicated at 24, for a purpose herein-after described.

The blocks D and E are each provided with a centrally disposed, downwardly projecting, cylindrical stem 25 and the projecting end of each drawbar is provided with an opening 26 adapted to receive the stem of one of the blocks. The stem of each block serves to swivelly connect the same to the corresponding drawbar, the block resting on the drawbar and the stem projecting below the same and having a collar 27 pinned to the lower end thereof to retain the block in position. Proper clearance is provided between the respective end walls 11 and the blocks D and E so that the latter will have free swinging movement in a horizontal plane.

The block E is preferably connected to the drawbar 12 at the gate end of the car 80 and the block D to the drawbar 12 at the opposite end of the car, and the cars are so disposed when coupled that the block D on the one car is disposed in opposed relation to the block E of the adjacent car.

The block D is embraced by the side members 19 of the yoke A and is provided with a transverse opening 28 of generally rectangular cross-section, the front and rear walls of the opening being curved as indicated at 29.

The set of spring plates C comprises a series of flat rectangular plates arranged face to face, forming together a spring unit adapted to absorb the shocks in both buff and draft. The plates composing the set are vertically disposed, and extend through the opening 28 of the block D with the opposite ends thereof projecting an appreciable distance beyond the respective sides of the block D, the set of plates fitting tightly between the curved front and rear walls of the opening 28.

The cups B—B are of like construction, each being of cylindrical form and having a pocket 29 formed therein, having parallel top and bottom walls and slightly flaring front and rear walls, the pockets at their inner ends corresponding in cross sectional

area to the area of the corresponding end of the set of plates C. Each of the cups B is rotatably mounted in the opening 23 of one of the side members 19 of the head 18 and is provided with a peripheral groove 30 within which engages the side of a retaining pin 31 driven into the corresponding side member 19. The opposite ends of the set of spring plates C are fitted in the respective cups B, and prevent the cups from turning.

As the yoke A is journaled on the cups B, it is mounted for swinging movement in a vertical plane and may be dropped out of the way to the dotted line position shown in Figure 1, to provide proper clearance when the car is in a restricted space, as when the same is being handled on the mine hoist.

The block E is provided with an upwardly opening, transversely extending, curved slot 33, thereby providing an upstanding hook member 34 adapted to coact with the eye 17. The slot 33 is correspondingly curved to the ring shaped eye and is of slightly greater width than the thickness of the ring thereof so as to freely accommodate the same. It will be evident that when the eye 17 is engaged with the hook 34, the buff shocks will be transmitted through the eye to the rear wall of the slot and the draft shocks will be sustained by the hook.

In draft action, it is evident that as the cars are pulled apart, the yoke A being held by the hook on the one car and the block D being relatively fixed to the other car, the yoke A will be pulled outwardly relatively to the block D, thereby flexing the set of spring plates C and cushioning the shock. In a buff action, as the cars approach each other, the yoke will be forced in a direction opposite to that just described, thereby flexing the springs in the opposite direction also. It will be evident, that by curving the front and rear walls of the opening 28 in the block D and flaring the pockets of the cups B, the maximum resiliency of the spring plates is utilized.

When the cars are uncoupled and the yoke A is in its pendant position as shown in dotted lines in Figure 1, the curved surface 24, which is normally the upper surface of the head 18 is disposed in vertical position and forms a buffing surface coacting with a rounded buffing surface 35 formed at the outer end of the block E.

Referring next to the embodiment of the invention illustrated in Figures 4 and 5, 110 indicates the flooring of each mine car, 111 the end wall and 112 the drawbar. The drawbars are in all respects similar to the drawbars illustrated in Figures 1, 2 and 3, being each provided with a downwardly extending lug 113 abutting the end of the flooring 110 and fixed to the car by means of a bolt 114 extending through the drawbar, flooring and a reinforcing member.

The connecting or coupling means illustrated in Figure 4 comprises, broadly, a yoke member A'; a sleeve B'; a set of spring plates C'; and two blocks D' and E'.

The member A' comprises a shank 116 having a pocket 117 at one end and a pair of spaced arms at the other end, embracing the block E'. Each of the arms has its free end enlarged vertically and provided with a centrally disposed, transverse, rectangular opening, having relatively flaring front and rear walls, the openings in the two arms being in alinement and adapted to receive the respective ends of the set of spring plates C'. The opposite ends of the set of spring plates C' project beyond the outer sides of the respective arms 119 and are retained in assembled position by a pair of pins 137, one at each end of the set, secured to laterally projecting lugs 138 on the corresponding arm 119. The block D' is provided with a stem 125 swiveled in the corresponding drawbar 112 and has a transversely extending cylindrical opening 139, in which the sleeve B' is journaled. The sleeve B' is of hollow construction, being provided with an opening 140 of generally rectangular cross section, adapted to accommodate the major portion of the spring unit comprising the set of spring plates C', the front and rear walls of the opening being curved similar to the walls of the opening of the block D previously described.

The block D' is also provided with a stem 125 swiveled in the corresponding drawbar 109 at the gate end of the car in a manner similar to the block E. At its upper side above the drawbar, the block E' is provided with a spherical head 141 adapted to engage within the pocket 117, when the cars are coupled together.

The yoke A' may be dropped out of the way in a manner similar to the yoke A, the sleeve B' rotating in the block D'.

The operation of the device shown in Figure 4 is in all respects similar to that previously described in connection with Figures 1, 2 and 3.

I have herein shown and described what I now consider the preferred manner of carrying out my invention, but the same is merely illustrative, and I contemplate all changes and modifications that come within the scope of the claims appended hereto.

I claim:

1. In a resilient shackle for vehicles, the combination with a yoke pivotally connected to the car to swing in a vertical plane; a spring resistance incorporated in said pivotal connection and co-acting with said yoke; abutment means on the end of the car coacting with the spring resistance; and means adapted for detachably connecting the yoke to the end of another car.

2. In a connector for cars, the combina- 130

- tion with a block swiveled to the end of a car, said block having abutment means thereon; of spring plates coacting with said abutment means; a yoke having abutment means thereon coacting with said spring plates, said yoke being mounted for swinging movement in a vertical plane; and means on the free end of said yoke for detachably connecting the same to another car.
- 10 3. In a connector for cars, the combination with a yoke having means thereon for detachably connecting it to a car; of a spring resistance comprising a plurality of flexible plates coacting with said yoke; and means secured to another car embracing said plates and holding the same against movement longitudinally of the car, said holding means and yoke being relatively movable longitudinally of the car and said yoke being rotatably mounted on said plates to swing in a vertical plane.
- 15 4. In a connector for cars, the combination with a yoke having means at one end for detachably connecting the same to a car; of a spring unit comprising a plurality of resilient plates; a block swiveled to the end of another car, said block having means thereon for holding said spring unit against movement relatively thereto; and means at 20 the other end of said yoke embracing said block for swingingly connecting said yoke to said spring unit for movement in a vertical plane.
- 25 5. In a connector for cars, the combination with a yoke pivotally connected to one end of a car for swinging movement in a vertical plane; a spring resistance coacting with said yoke, said resistance being connected to said car; a buffing surface on the adjacent 30 end of another car; and a buffing surface on said yoke adapted to be brought into operative position to coact with said first named buffing surface when said yoke is in a pendant position.
- 35 45 6. In a connector for two adjacent vehicles,
- the combination with a member adapted to be attached at one of its ends to the end of one of the vehicles; of a universal joint connection for attaching the opposite end of said member to the adjacent end of the other vehicle, said universal joint connection having embodied therein resilient shock absorbing means.
7. In a connector for cars, the combination with a connecting device adapted to inter-connect adjacent cars; of means for pivotally securing one end of said device to one of said cars, the pivotal connection including cushioning means incorporated therein, said device having a buffing surface thereon, adapted to be arranged in operative position only when said device is in inoperative position.
8. In a connector for cars, the combination with a connecting yoke adapted to inter-connect adjacent cars; of means for pivotally securing one end of said yoke to one of said cars so that said yoke may be swung in a vertical plane, said yoke having a buffing surface thereon so arranged as to lie on the top of said yoke when the yoke is in its operative position and to be swung to operative position when said yoke is swung to inoperative position.
9. In a connector for cars, the combination with a yoke having means thereon for detachably connecting it to a car; of a spring resistance co-acting with said yoke; and means secured to another car engaging said spring resistance and holding the same against movement longitudinally of the car, said holding means and yoke being relatively movable longitudinally of the car, and said yoke being mounted to swing in angular planes relative to said holding means.
- In witness that I claim the foregoing I have hereunto subscribed my name this 26th day of September, 1923.

JOHN F. O'CONNOR.
